UNITED STATES PATENT OFFICE.

GEORGE F. DICKERSON, OF DETROIT, MICHIGAN.

VENTILATOR.

1,243,146.

Specification of Letters Patent. Patented Oct. 16, 1917.

Application filed April 21, 1916. Serial No. 92,590.

To all whom it may concern:

Be it known that I, GEORGE F. DICKERSON, a citizen of the United States of America, residing at Detroit, in the county of Wayne 5 and State of Michigan, have invented certain new and useful Improvements in Ventilators, of which the following is a specification, reference being had therein to the accompanying drawings.

10 This invention relates to ventilators and the principle of my invention may be embodied in window, cellar, car and building ventilators.

15 The primary object of my invention is to provide a novel ventilator that may be easily built into a wall and the ventilator includes baffle members or plates which insure an indirect ventilation without a draft or current of air in either direction which 20 would tend to unduly exhaust air from a compartment or flood the same with cold air.

25 Another object of my invention is to provide a wall ventilator by which fresh dry air can be admitted to a part of a building when the weather is seasonable and that may be closed entirely when the weather is cold or damp, and provision is also made for excluding flies, small insects and animals, particularly when the ventilator is built into a 30 cellar wall, for instance as an air intake to a hot air furnace or other heating apparatus.

35 A further object of my invention is to provide a telescopic or extensible ventilator that may be built into walls of various widths, the ventilator including novel baffle members or plates at the outer end thereof and a register, grating or closure 40 members at the inner end of the ventilator.

45 A still further object of my invention is to provide a ventilator of the above type wherein the parts are constructed with a view of reducing the cost of manufacture and at the same time retain the features by which simplicity of construction, durability and ease of assembling are secured, and with the above and other objects in view my 50 invention resides in the novel construction to be hereinafter described and then claimed.

Reference will now be had to the drawing, wherein—

55 Figure 1 is a longitudinal horizontal sectional view of a ventilator in accordance with my invention;

Fig. 2 is a vertical cross sectional view of the same, and

Fig. 3 is a plan of a telescopic or extensible ventilator mounted in a wall or other support.

60 The ventilator comprises a rectangular metallic shell having the side walls 1 and top and bottom walls 2 with the ends of said shell open. The outer end of the shell is provided with a marginal flange 3 disposed at right angles to the walls of the shell and connected to this flange by rivets 4 or other fastening means is a rectangular frame 5, preferably made of one or more Z bars providing outwardly extending 65 flanges 6 and inwardly projecting flanges 7.

70 Interposed between the flanges 3 of the shell and the flanges 6 of the frame 5 are the marginal edges of an inner baffle plate or member 8 provided with top and bottom 75 openings 9 and a central longitudinal outwardly projecting rib or baffle 10. The openings 9 and the baffle 10 correspond in length to the shell and the baffle 10, which is pressed out from the plate or member 8 80 and angular in cross section, adds rigidity to the member or plate.

85 When the ventilator is used in connection with a cellar wall or any place where flies or insects are liable to enter the ventilator, a screen 11 may have the marginal edges thereof anchored between the flanges 3 of the shell and the baffle member 8, thus precluding any possibility of flies or other insects passing through the openings 9 into 90 the shell.

95 Riveted or otherwise secured to the inwardly projecting flange 7 and the frame 5 is an intermediate baffle member or plate 12 having a central longitudinal slot or opening 13 in proximity to the ridge or baffle 10, and the marginal edges of the opening or slot 13 are bent inwardly, as at 14, with the ends of the bent in portions engaging the flanges 7 at the sides of the ventilator structure, thus properly centering the intermediate baffle plate or member 12 relative to 100 said frame.

105 The same fastening means for the intermediate baffle member or plate 12 is employed for holding an outer baffle member or housing 15, in parallelism with the inner baffle member or plate 12. The housing 15 is made of sheet metal with the ends thereof stepped to rest on the member or plate 110

12 and to extend onto the outwardly extending flanges 6 of the frame 5, adjacent the side walls 1 of the ventilator. The rivets 4 may coöperate with fastening means 16 of the baffle member 12 in holding the housing 15 relative to the frame 5. The top and bottom of the housing 15 are open and in said housings are vertically disposed baffle members 17, in the form of Z bars 10 connected to the inner wall of the housing 15 and to the intermediate baffle member 12, said vertically disposed baffle members 17 being in spaced relation, corresponding in depth to the housing 15 and crossing the 15 opening or slot 13 of the intermediate baffle member 12.

Connected to the walls 1 and 2 at the inner end of the ventilator shell is an inner frame 18 providing lateral flanges, and connected to the flanges of said frame by rivets or other fastening means is a register frame 20 having interstices 21.

Trunnioned or otherwise mounted between the side walls 1 of the shell, to swing to and 25 from the top and bottom walls 2, are closures or doors 22 adapted to have the free edges thereof meet at the inner side of the grate 20 and close said grate. Each door has a pivoted notched arm 23 extending 30 through interstices of the grate and it is through the medium of these notched arms that the closures 22 can be adjusted relative to the grate and held in adjusted position.

When the ventilator structure is built into a wall, as shown in Figs. 1 and 2, it is impossible for wind or a current of air traveling in a lateral direction to enter the upper and lower open end of the housing 15 and the effect of any suction produced by passing 35 currents of air is broken up or retarded by the intermediate and inner baffle members 12 and 18. The inner and intermediate baffle members provide an indirect or tortuous passage into and out of the shell and 40 by having the openings 9 staggered relative to the openings or slots 13, there is sufficient retardation of air to prevent the setting up of excessive current that would tend to rapidly exhaust warm air from a compartment 45 or flood a compartment with cold air. However, the register frame or closures will permit of the amount of air passing through 50 the ventilator to be regulated, but in some instances the closure may be dispensed with, particularly when the ventilator is constructed as a window attachment.

In Fig. 3 of the drawings there is illus-

trated a slight modification of my invention, wherein the shell is composed of two telescopic members 24 and 25 and these members may be adjusted to properly position the inner and outer ends of the ventilator relative to walls of the various widths. The members 24 and 25 may be connected by tie rods 26 and otherwise the inner and outer 60 ends of the ventilator are identical with the preferred form of construction.

While in the drawings, there are illustrated the preferred embodiments of my invention, it is to be understood that the structural elements are susceptible to such changes, in size, shape and manner of assemblage, as fall within the scope of the appended claims.

What I claim is:—

1. A ventilator comprising a shell, a frame carried by the end thereof, an inner baffle member between said shell and said frame and having longitudinal top and bottom openings with a central projecting and longitudinally disposed baffle rib, an intermediate baffle member on said frame having a longitudinal opening at the baffle rib of said inner baffle member with the marginal edges of the opening bent in toward said baffle rib, and a housing on said frame in communication with said shell and having the upper and lower ends thereof open.

2. A ventilator comprising a shell having an outstanding flange, at one end thereof, a frame having inwardly and outwardly projecting flanges, an inner baffle member secured between the flanges of said shell and the outwardly projecting flanges of said frame, said inner baffle member having longitudinal top and bottom openings with a central projecting and longitudinally disposed baffle rib that has its ends abutting said frame and in proximity to the inwardly projecting flange thereof, an intermediate baffle member on the inwardly projecting flange of said frame and having a longitudinal opening at the baffle rib of said inner baffle member, and a housing on said frame in communication with said shell and having the upper and lower ends thereof open.

In testimony whereof I affix my signature in the presence of two witnesses.

GEORGE F. DICKERSON.
